FIG.1

UNITED STATES PATENT OFFICE

2,557,548

SIDE SLIPPING WEFT DETECTOR

Clarence R. Kronoff, Worcester, and George N. Peterson, Grafton, Mass., assignors to Crompton & Knowles Loom Works, Worcester, Mass., a corporation of Massachusetts

Application February 18, 1950, Serial No. 145,008

11 Claims. (Cl. 139—271)

1

This invention relates to improvements in side slipping weft detectors for looms and it is the general object of the invention to provide improved means for moving the detector finger of the detector mechanism out of the path of the incoming bobbin at the time of bobbin transfer.

Multicolor weft replenishing looms generally have the weft detector located at the magazine end and provision must be made for moving the detector forwardly out of the path of the incoming bobbin as the latter is pushed into the depleted shuttle by the transerrer arm. In the past this has generally been accomplished by moving the entire detector mechanism forwardly on some form of sliding guide, but when the detector finger is mounted on a lever there is likelihood that the latter may swing incident to its forward movement and give a false indication of weft exhaustion.

It is an important object of the present invention to mount the detector finger for sliding movement on a pivoted carrier which is mounted on a stationary support, and provide for moving the detector finger forwardly with respect to the lever whenever a weft replenishing operation occurs in such manner that the carrier will not swing to give a false indication.

It is another object of the invention to provide a detector lever or carrier with a detector finger of simple form having a lateral offset to be engaged by a retracting or withdrawing member which is moved by the transerrer arm on a weft replenishing beat of the loom, the member and offset cooperating with the finger and a spring attached thereto to prevent turning of the lever and thereby preventing a false indication.

It is another object of the invention to make the retractor member in the form of a wire having sliding engagement with a guide fixed to the stationary detector support and having an offset arm for engagement with some part moving with the transerrer arm. The retractor is preferably made of wire and is resilient and can be readily bent when being applied to and removed from the stationary guide.

With these and other objects in view which will appear as the description proceeds, the invention resides in the combination and arrangement of parts hereinafter described and set forth.

In the accompanying drawings, wherein a convenient embodiment of the invention is set forth:

Fig. 1 is a side elevation of part of the weft replenishing mechanism having the invention applied thereto, the shuttle box, shuttle and lay being in cross section, and the parts being in normal position.

2

Fig. 2 is an enlarged plan view looking in the direction of arrow 2, Fig. 1, the hanger for the detector mechanism being shown in section.

Figs. 3 and 4 are detailed transverse vertical sections on lines 3—3 and 4—4, respectively, of Fig. 2.

Fig. 5 is a side elevation of the weft detector looking in the direction of arrow 5, Fig. 4, and in the direction opposite to that in which the detector is seen in Fig. 1.

Fig. 6 is a perspective view of the detector finger.

Fig. 7 is a perspective view of the retractor member, and

Fig. 8 is a diagrammatic view indicating the detector in non-indicating position in full lines and in indicating position in dotted lines.

Referring particularly to Fig. 1, the loom frame 10 has mounted thereon the foot 11 of a weft replenishing mechanism not specifically shown herein but of any approved type, such for instance as the rocking two-color type or the stationary four-color type. Foot 11 has a transerrer stud 12 secured thereto on which is pivoted a transerrer arm 13 having a transerrer shoe 14 secured to the rear end thereof, at the right in Fig. 1. Depending from the hub 15 of the transerrer lever are two arms 16 and 17 which support a stud 18. Pivoted to the latter is a latch carrier 19 to which a transerrer latch 20 is secured as at 21. The stud 18 extends to one side of depending arm 16 as suggested in Fig. 2 for a reason to be set forth hereinafter.

The lay 22 supports a shuttle box 23 in which 35 a shuttle S is located on replenishing beats of the loom. During a weft replenishing operation the depleted bobbin 24 in the shuttle is replaced by a full bobbin 25, the depleted bobbin passing down through a slot 26 in the lay, and the full bobbin passing downwardly into the shuttle and being held by the usual bobbin clips (not shown). The shuttle box and front wall 27 of the shuttle S have aligned slots or opening 28 and 29, respectively, for reception of a weft detector finger indicated generally at F.

During loom operation a bunter 30 secured to the lay ordinarily sweeps back and forth in a path above the latch 20, but when a weft replenishing operation is to occur mechanism not shown herein but well understood lifts the latch into the path of the bunter 30, and as the lay advances or moves to the left, Fig. 1, the latch and carrier 19 are moved forwardly by the bunter to cause the transerrer foot 14 to descend and insert the full bobbin 25 into the shuttle S. At this time it is necessary to move the detector finger F out of the

shuttle a distance sufficient at least to clear the incoming bobbin. It will be understood that the bobbin transfer occurs when the lay is on front center and at this time the detector finger F is normally in the shuttle performing a weft detecting operation.

The present invention relates to a type of side slipping weft detector in which the finger F is mounted for sliding movement on a carrier lever mounted on a fixed pivot by stud 18 for moving the finger F forwardly. Referring particularly to Figs. 1 and 2, a small stand 35 is secured as at 36 in fixed position on the transerrer stud 12 and extends downwardly and preferably rearwardly. A hanger 37 shown herein as made of sheet metal is held for vertically adjusted position by screws 38 screw threaded into the stand 35 and passing through a vertical slot 39 in the upper part of the hanger 37. The lower part of the latter is bent horizontally to provide a supporting foot 40 extending under a plate or support 41. The latter has slots 42 therein through which extend bolts 43 which hold the support 41 in stationary position but permit it to be adjusted back and forth on the hanger.

The support 41 has secured thereto and upstanding therefrom a stud 45 surrounded by the hub 46 of a detector carrier lever 47. A slide bearing block 48 is secured to lever 47 in any approved manner, as by screws 49, and has a horizontal hole 50 drilled therethrough extending in a back and forth direction. Block 48 is also provided with a slot 51 parallel to hole 50 opening laterally away from hole 50, or to the right as viewed in Fig. 3.

The previously mentioned detector finger F is preferably made of resilient metallic wire and has two parallel strands or branches 52 and 53 the former of which has secured to the rear end thereof a bobbin tip feeler 54. The branch 53 is much shorter than branch 52 and is received by the hole 50, while the longer branch 52 fits into the slot 51. The two branches are of such length that the rear part of branch 52 can be placed in the slot 51 and then as the finger is moved rearwardly the shorter branch 53 will enter the hole 50.

As shown more particularly in Fig. 2 both of the branches 52 and 53 are provided with lateral offsets shown at 55 and 56, respectively, which are joined by a bend in the wire of which the finger F is made to form a lateral arm 57. A light tension spring 58 extends between a rear lug 59 upstanding from and rigid with the stationary support 41 and the rear part 56 of lateral arm 57. The effect of spring 58 is to hold the finger F normally in rearward position and also hold lateral arm 57 against lever 47 so that the latter will normally be in its non-indicating position shown in full lines in Fig. 2.

A normally open electric switch E is secured to the under side of support plate 41 and has a plunger 60 for engagement with a finger 61 on lever 47. Normally finger 61 engages the support to serve as a stop to limit movement of the lever and also depresses plunger 60 to keep switch E open, but if lever 47 rocks on its pivot clockwise, Fig. 2, the plunger is unrestrained and permits closure of the switch.

A particular form of the detector finger F, lever 47, and switch E, thus far described is not specifically claimed therein, but forms the subject matter of a copending application Serial No. 137,781, filed January 10, 1950, by the present joint applicant Kronoff.

The forward part of support 41 has secured

thereto a bearing block 65 similar to block 48. This block has a backwardly and forwardly extending hole 67 therethrough similar to hole 50 and a laterally opening slot 68 similar to slot 51 parallel to hole 67. The hole 67 and slot 68 are guideways for a retracting or withdrawing member designated generally at R. The retractor is conveniently made of bent wire and has short and long parallel arms 69 and 70, respectively, slideable in their respective guideways. The rear end of the arm 70 has an upturned end 71 normally lying behind and preferably spaced from the lateral arm 57. The two arms 69 and 70 are joined at their forward ends and are bent upwardly to provide a retracting arm 72 for engagement with the stud 18.

As shown more particularly in Fig. 2 the part 56 of lateral arm 57 which engages the upturned end 71 is inclined in a direction forwardly, to the left in Fig. 2, and laterally from the branches 52 and 53 of the detector finger F.

Under normal conditions the detector parts will be in the full line position shown in Figs. 2 and 8, the pivoted carrier lever 47 being in its normal non-indicating position to maintain switch E open. The depending finger 61 of lever 47 engages the support 41 to limit angular motion of the lever in a counter-clockwise direction as viewed in Fig. 2, see Fig. 4. If there is a sufficient supply of weft in the shuttle as the lay advances on a weft detecting beat the tip 54 will be partly embedded in the weft and the finger F will slide forwardly with respect to the block 48, and the detector lever 47 will be held against angular movement on its pivot 45. If, on the other hand, the feeler tip engages a depleted bobbin, such as 24, the tip will slide along the bobbin and lever 47 will move angularly from the full line to the dotted line position of Fig. 8 due to the fact that the detector finger arm 52 is offset from the pivot of the lever in the direction of the length of the surface or bobbin being detected.

When the detector lever moves angularly it will move finger 61 away from plunger 60 and switch E will close to give indication of weft exhaustion by means of any of the known types of electric circuits (not shown), after which the transerrer arm will effect bobbin transfer. As the transerrer arm 14 descends the stud 18 moves forwardly and engages the upstanding arm 72 of the retractor R, thus moving the latter forwardly as suggested in dotted lines in Fig. 2 and causing the upturned rear end 71 of the arm 70 to engage the lateral arm 57 and move the finger F to the forward dotted line position shown in Fig. 2 where its tip 54 will be clear of the path of the incoming bobbin 25. Since the retractor engages the offset arm 57 at a point beyond spring 58 with respect to the feeler finger branches 52 and 53 the detector lever 47 will be prevented from turning and the switch E will remain open, a condition which is desirable inasmuch as an indication of weft exhaustion should not be given on a weft replenishing operation of the loom.

As the lay starts to move rearwardly after bobbin transfer at front center the transerrer arm 14 will rise in usual manner and the spring 58 will move the finger F rearwardly and in doing so will move the retractor R rearwardly by engagement with arm 57.

The upturned end 71 is so located with respect to the offset arm 57 that it does not interfere with the rocking motion of the detector finger 75 when the latter gives indication of weft exhaus-

tion, as will be apparent from an inspection of Fig. 8. It will also be understood that inasmuch as part 56 of lateral arm 57 is oblique with respect to the direction of motion of the retractor and is inclined forwardly from the finger F the latter will be held against clockwise angular movement around the pivot stud 45 as viewed in Fig. 2, as the retractor moves forwardly. This last named relationship assists the branches 52 and 53 and spring 58 to prevent angular motion of the pivoted carrier member 47.

From the foregoing it will be seen that the invention sets forth a weft detector mechanism all parts of which remain stationary except the weft detector finger when the latter is moved forwardly incident to a weft replenishing operation of the loom. The carrier lever 47 is mounted on a fixed pivot, and since the support 41 remains stationary and unmoved during the transfer operation the carrier is not acted on by any force tending to move it in a direction to give a false indication. The retractor R engages the offset arm 57 at a point beyond the spring 58 with respect to the finger F and because of this relationship the spring tends to prevent angular motion of the carrier lever 47. Furthermore, the forward inclination of part 56 of the lateral arm 57 from the branches 52 and 53 cooperate with the upturned end 71 to prevent angular motion of the lever 47 when the finger is withdrawn by the retractor. The retractor is guided in a block 65 which may be a duplicate of block 48 and has parallel arms which are sufficiently resilient to be sprung to permit them to be slidably engaged with the block 65. Also, the switch plunger exerts a given force tending to turn the lever toward its indicating position but the spring acting through the finger F exerts a greater force to prevent turning of the lever by plunger 69 when the retractor moves the finger forwardly.

Having thus described the invention it will be seen that changes and modifications of the foregoing specific disclosure may be made without departing from the spirit and scope of the invention.

What is claimed as new is:

1. In a weft detecting mechanism for a weft replenishing loom having a weft surface to be detected, a support fixed with respect to the loom, a detector lever pivoted on said support, a guide on the lever extending in a direction toward and from said surface, a detector finger slidable on said guide and having a feeler tip offset from the axis of the lever in the direction of the length of said surface, means indicating weft exhaustion when the lever moves angularly on said support, a lateral arm on said finger, a retractor operative on a weft replenishing operation of the loom to engage said arm and move the finger on said guide in a direction away from said surface, and a spring having one end thereof fixed with respect to said support and having the other end thereof connected to said lateral arm between said guide on the lever and said retractor, said spring, finger and guide effective during movement of the finger by the retractor to prevent angular motion of the latter.

2. In weft detecting mechanism for a weft replenishing loom having a weft surface to be detected, a support fixed with respect to the loom, a pivot on said support, a detector lever mounted on said pivot for angular movement with respect to said support, a detector finger slidable on said support in a direction toward and from said surface and having a feeler tip offset from said pivot

in the direction of the length of said surface, means indicating weft exhaustion when the lever moves angularly on said support in a given direction, a lateral arm on said finger extending from the latter to a position forward of said pivot, a retractor operative on a weft replenishing operation of the loom to engage said lateral arm and move the finger slidably on said lever in a direction away from said surface, and a spring having one end thereof fixed with respect to the support and having the other end thereof connected to said lateral arm between said retractor and said finger, said spring and finger cooperating during movement of said lateral arm by said retractor to prevent angular motion of the detector lever in said given direction.

3. In weft detecting mechanism for a weft replenishing loom having a weft surface to be detected, a stationary pivot, a detector lever mounted on the pivot effective to indicate weft exhaustion when turning in a given direction on said pivot, a detector finger guided for slidable movement on the lever in a direction toward and from said surface and having a feeler tip for engagement with said surface offset from said pivot in the direction of the length of said surface, a lateral arm on said finger forward of said pivot, a retractor operative during a weft replenishing operation of the loom to engage said lateral arm and slide the finger on said lever forwardly with respect to said surface, and a spring having one end thereof stationary and having the other end thereof connected to said lateral arm between said retractor and said finger, said spring and finger cooperating when said lateral arm is moved by the retractor to prevent angular motion of the detector lever.

4. In weft detecting mechanism for a weft replenishing loom having a surface to be detected, a stationary support, a detector lever mounted for angular movement on said support, an electric switch mounted on said support held open by the lever when the latter is in non-detecting position but tending to close and normally exerting a force on said lever tending to move the same toward indicating position, a detector finger slidable on said lever and guided thereby for movement toward and from said surface, a lateral arm on said finger, a spring having one end thereof fixed with respect to the support and having the other end thereof operatively related to said lateral arm at a given point along the length of the latter, and a retractor operative on a weft replenishing operation of the loom to engage said arm at a point beyond said given point with reference to the finger to slide the latter away from said surface, said spring and finger effective when said arm is moved by said retractor to prevent movement of the detector lever to the indicating position thereof.

5. In weft detecting mechanism for a weft replenishing loom having a surface to be detected, a stationary support, a pivot on said support, a detector lever mounted for pivotal movement on said support, an electric switch on said support normally exerting a given force on said lever tending to move the latter from the normal position thereof toward the indicating position thereof, a guide on said lever, a detector finger guided for sliding movement on said guide relative to the lever in a direction toward and from said surface, a lateral arm on said finger forward of said pivot, a retractor effective on a weft replenishing beat of the loom to engage said arm and slide the finger forwardly relatively to the

guide, and a spring exerting a force on said arm in a direction toward said surface at a point between said retractor and said finger, said arm engaging said lever and said spring effective normally to overpower said given force, said spring and finger and guide during forward movement of said lateral arm by said retractor exerting a force on said lever opposite to and greater than said given force and preventing angular movement of the detector lever on said pivot.

6. In a weft replenishing loom, a stationary support, a pivot on said support, a detector lever mounted on said pivot for angular motion relatively to said support, guide means on the lever, a detector finger guided for sliding movement on said guide relative to said lever, a lateral arm projecting from said finger forward of said pivot, a retractor slidably mounted with respect to and supported by said support and engaging said lateral arm at a given point, and a spring having one end thereof fixed with respect to said support and having the other end thereof attached to said lateral arm between said given point and said finger and cooperating with said arm to hold said lever normally in non-indicating position, said retractor when sliding relatively to said support in a direction away from said pivot causing said finger to slide relatively to the guide and said spring and finger and guide being effective during said forward movement of the retractor to hold said lever in the non-indicating position thereof.

7. In a weft detector for a weft replenishing loom, a stationary support, a pivot on said support, a detector lever mounted for angular movement on said pivot, a detector finger slidable on said lever, a lateral arm on the forward part of said finger engaging said lever, a retractor forward of the pivot, means on said support guiding the retractor for movement along a given path in a direction away from said pivot, a spring on the support engaging said lateral arm at a point between said retractor and said finger and cooperating with said arm to hold the detector lever normally in non-indicating position, said lateral arm having a part thereof oblique with respect to said path and inclined forwardly from said finger, said retractor effective when moved in said given direction to engage said part of said lateral arm and slide the finger forwardly relatively to the lever and effective due to engagement with said part to prevent angular movement of the lever around said pivot.

8. In a weft detector mechanism for a loom, a support, a detector lever pivoted on said support, a weft detector finger, guide means on said lever on which the finger is slidable at one side of the axis of the lever, a lateral arm on said finger forward of said axis, a retractor mounted

on said support for sliding movement forwardly from said axis and having a part for engagement with said arm, and a spring having one end thereof held fixed with respect to the support and having the other end thereof engaged with said arm at a point between said finger and said retractor, said spring and arm cooperating to hold the lever in normal position on said support, said retractor when sliding forwardly from said axis causing said part thereof to slide the finger forwardly on the guide means and the latter and the spring and finger cooperating to hold the lever in said normal position thereof.

9. In a weft detector, a support, a pivot on the support, a detector lever movable angularly on said pivot, a detector finger guided for straight line movement on said lever at one side of the pivot, an arm on said finger extending laterally from the finger and forwardly of the pivot, a retractor, a guide block fixed to the support on which the retractor is slidable in a direction toward and from said pivot, and a spring exerting a rearward force on said arm between the finger and retractor, said retractor when moved relatively to said block in a direction away from said pivot cooperating with said arm to slide the finger forwardly relatively to the lever and the spring and finger cooperating to prevent angular movement of the lever on said pivot.

10. In weft detecting mechanism having a detector finger mounted for sliding movement on a detector lever pivoted to a support, a guide secured to the support and having two spaced parallel guideways therein extending in a direction toward and from the lever, and a retractor slidably mounted on said guide for movement on the latter in a direction away from the lever, said retractor comprising a bent wire having two parallel arms, one in each of said guideways, one of said arms being effective to slide the detector finger on said lever when the retractor moves relatively to the guide away from the lever.

11. The weft detector mechanism set forth in claim 10 wherein said one arm has the end thereof adjacent to the lever upturned for engagement with the detector finger and the guideway for said one arm is an open slot in the guide opening away from the other guideway.
